UNITED STATES PATENT OFFICE

113,162

DESIGN FOR A CHANGEABLE EXHIBITOR

George A. Gast, Chicago, Ill., assignor to Community Educational Clubs, Inc., Chicago, Ill., a corporation of Illinois

Application November 8, 1938, Serial No. 80,968

Term of patent 14 years

To all whom it may concern:

Be it known that I, George A. Gast, a citizen of the United States, residing at Chicago, in the county of Cook and State of Illinois, have invented a new, original, and ornamental Design for a Changeable Exhibitor, of which the following is a specification, reference being had to the accompanying drawing, forming part thereof.

In the drawing,

I claim:

The ornamental design for a changeable exhibitor, as shown and described.

GEORGE A. GAST.
